BIRD FEEDER OR THE LIKE

Donald G. Clever, San Francisco, Calif., assignor to
Proen Products Co., a corporation of California

Filed Dec. 26, 1961, Ser. No. 68,065

Term of patent 3½ years

(Cl. D31—2)

Fig. 3.

FIG. 4.

FIG. 5.

FIG. 1 is a view in side elevation of a bird feeder, showing my new design, the opposite side not shown having substantially the same appearance.

FIGURE 2 is a front view in elevation;

FIGURE 3 is a top plan view thereof;

FIGURES 4 and 5 are, respectively, rear and frontal views in perspective of the bird feeder of my new design.

I claim:

The ornamental design for a bird feeder or the like, as shown and described.
